UNITED STATES PATENT OFFICE

ERNEST A. FEUSTEL, OF CARLSTADT, NEW JERSEY, ASSIGNOR TO ALFRED HOFFMANN, INCORPORATED, OF WEST NEW YORK, NEW JERSEY, A CORPORATION OF NEW JERSEY

KNITTING MACHINE

Application filed April 14, 1931. Serial No. 529,982.

This invention relates to knitting machines, and has reference more particularly to the improvement of certain portions of the mechanism and operation of straight knitting machines such as are used for the manufacture of full fashioned knitted hosiery. The improvement is shown, for purposes of illustration, applied to a knitting machine of the Cotton type, that is to say a knitting machine which employs banks of united needles operated in conjunction with a series of sinkers and a series of dividers, and means for actuating these in cooperation, including a series of jacks swingable in succession to operate the sinkers; a number of makes of machines of this type being in extensive commercial use.

The general object of the present invention is to improve the operation of the series of jacks and their actuation of the sinkers. As the sinkers control the formation of the successive courses of loops a highly accurate operation is desirable to prevent defects in hosiery, such as stripes, uneven fabric and the like, due to irregularity of action of the sinkers. In a machine of the kind referred to the jacks are swingable in succession to operate the sinkers, and it is customary to mount the jacks independently and more or less loosely upon a fixed axle or rod upon which they may independently swing when thrown forwardly by the slurcock or cam member to thrust the sinkers forwardly and form the loops; this loose fit being due to a construction including a semi-circular bearing contact that permits individual extraction and replacement of jacks without removing the axle from the bed. Owing to the loose fit of the jacks upon their axle, and the sudden rapidity with which they are put into motion by the slurcock it has been found that there is a tendency of the jacks to lift or become displaced slightly with relation to their axle. This action is the cause not merely of wear and reduced life of the jacks, but also of irregular knitting action, introducing differences in movements of the sinkers, which, although minute, give a noticeable effect in the completed product, and sometimes result in undesirable stripes and other defects

in the fabric. The particular object of this invention is to provide an improved construction and relation of the jacks and their axle so as to obviate the looseness, the wear and the irregular action referred to, while yet retaining the adaptability of the mechanism to quick removal and replacement of work or defective jacks, or the interchange of an entire series of jacks for others.

Other and further objects and advantages of the present improvement will be pointed out in the hereinafter following description of an illustrative embodiment thereof or will be apparent to those skilled in the subject. To the attainment of such objects and advantages the present invention consists in the novel knitting machine and the novel features of combination, cooperation and construction herein illustrated or described.

In the accompanying drawings Figure 1 is a perspective view of the near end of a series of jacks and surrounding parts seen obliquely from the rear and above.

Fig. 2 is a face view of one of the jacks detached, and showing its relation to the sinker and jack spring.

Fig. 3 is a perspective view of a portion of the length of the jack axle.

Fig. 4 is a diagrammatic side elevation showing the normal relation between each of the jacks and the jack axle, and in dotted lines the jack position when oscillated forwardly to actuate a sinker.

Fig. 5 is a view similar to Fig. 4, but showing the axle rotated around to release position, and in dotted lines showing in a general way the mode and direction of extraction or disengagement of the jack from the axle.

Figs. 6 and 7 are views corresponding with Figs. 4 and 5 of a modified embodiment.

Figs. 8 and 9 are views corresponding to Figs. 4 and 5 of a further embodiment.

Some of the general parts of the apparatus, which may be of any known form or type, include the jack bed comprising a bottom piece 10 and end pieces 11 assembled and held rigidly together by bolts. The jack bed end pieces are of characteristic shape, and in part they align substantially with a series of guide walls 12 constituting a so-called

comb or multiple guide for the jacks, these guide walls being held in position by grooves formed in the bottom piece 10 and corresponding grooves formed in an upper bar 13 attached to the upper rear side of the end piece and in a rear bar 14 also secured to the end pieces, the bars 13 and 14 cooperating with the bottom 10 to rigidify the entire jack bed.

- 10 The jack axle 15 is in the nature of a cylindrical rod extending the length of the jack bed and taking its support in the end pieces 11 and the guide walls 12. The general plan of this invention is to give to the axle and 15 jacks a construction and relation by which a superior bearing is afforded for the constant oscillations of the jacks holding them precisely to their swinging movement, while, when the machine is out of operation the axle may 20 be shifted, as manually, to effect a release of the jacks to permit any one or more to be extracted and replaced. Various kinds of shift movements of the axle may be used for the purpose, but a rotary shift is preferred, as 25 will be explained.

As shown in the separate figures the jack axle is of special construction, being cut away or milled with a recess 16 at one side. The intact part of the circumference substantially 30 exceeds a half circle, which is interrupted by the recess, which recess meets the circumference at an upper point or apex 17 and a lower point or apex 18, the purpose of which will be subsequently explained.

- 35 The series of jacks 20 may be generally of the usual type having a nose 21 adapted to push forwardly against the sinker 19. A substantially concentric surface 22 is shown, usual in such jacks, adapted to cooperate 40 with a stop bar or hold down, to be referred to. The jack tail 23 is adapted to cooperate with a jack spring 24.

Each jack is formed with an aperture 25, which is intended to engage the jack axle or 45 rod 15, but which differs from the usual U-shape jack aperture, having no more than a semi-circular bearing, in that it is circular in shape for substantially more than a semi-circumference, but with an open gap at the 50 outer side of sufficient actual width for lateral disengagement from the axle, as will be described. Where the gap interrupts the circumference of the aperture 25 are formed upper and lower points or apexes 26 and 27.

- 55 The axle 15 is adapted to be rotated in its bearing between its normal position wherein all of the jacks are confined but independently swingable upon the axle, and its release position wherein any jack may be independently 60 disengaged from or engaged with the axle. For the purpose of such rotary adjustment of the axle its outer end is shown extended beyond the end wall 11 to where it has applied to it a handle 30, the hub of 65 which is made fast to the axle. A latch de-

vice 31 is shown cooperating with positioning points or stops 32 and 33 determining the normal and release positions respectively of the axle, the arrangement being such that the axle is fixedly held or locked when in normal position.

In dotted lines on Fig. 1 is indicated a stop bar or hold down 35 attached to the end pieces 11 and adapted to cooperate with the jack surfaces 23 to hold them against accidental disengagement from the axle. Such stop bar was essential in jack mechanisms as previously constructed, but may be dispensed with in the present invention, affording the additional advantage that removal and replacement of such bar is no longer necessary to permit the extraction and displacement of one or more jacks. Due to the circular engagement of jack aperture and axle circumference for considerably more than a semi-circumference, preferably between 190° and 70 270°, the jacks are normally locked upon the axle throughout their swinging operation, which both avoids detachment and affords a very effective and smooth bearing, 75 positively preventing looseness, irregular movement and wear, and insuring a more evenly knitted fabric.

Various accompanying and surrounding pieces of mechanism and devices are omitted 80 as being well understood to those skilled in the subject, although the sinkers 19 are indicated; and the drawings indicate the jack spring 24, one of which is provided for each 85 jack, the spring having a grooved hump co- 90 operating with the tail 22 of the jack in each of its two positions, so as to hold the jack 95 yieldingly in either position.

The drawings indicate also the slurcock or 100 jack actuator 37 which is moved longitudinally for the formation of each course of loops, and operates successively on the jacks to cam them forwardly and give successive operation of the sinkers as each course of yarn is fed to the needles, in well known manner.

The operation of the invention has been 110 largely indicated. Normally the jack axle is set as seen in Fig. 4. The jacks are confined and locked upon the axle, giving a smooth oscillation. Preferably the jack 115 aperture is of greater circumferential extent than the axle recess, as seen in Fig. 4, so that the jack may swing without its bearing surface overhanging the axle recess, the apexes 120 26 and 27 moving always upon the bearing surface of the axle. The full and dotted lines indicate the extreme positions. When the jacks are swung forward to the dotted position they always take the same motion and give the same action to the sinkers as desired.

When one or more jacks are to be replaced the axle may be rotated to the release position as in Fig. 5. Any jack may then be pulled out by hand. The motion may com- 125

mence with a swing so that the apex 27 at the lower side of the jack aperture gap enters the axle recess. This allows the top apex 26 to clear the axle, as the dotted position shows, 5 and the jack readily comes out. The axle might be rotated to advantage during the extraction. The replacement of a new jack is accomplished by reverse movements to those described, the axle being finally rotated back 10 to normal position and there locked.

The same principle is illustrated in the modification of Figs. 6 and 7, although the recess 16^a of the axle 15^a in this embodiment is of a different form. Instead of being milled out as a simple groove the metal is 20 gradually shaped away from the lower apex 18^a, thence forming a deep notch which terminates at the upper apex 17^a. The jack aperture 25^a may have upper and lower apices 26^a and 27^a substantially the same as in Figs. 4 and 5. The mode of detachment will be substantially the same as in Figs. 4 and 5, inasmuch as the jack can pivot about the lower axle apex 18^a, its apex 27^a swinging 25 or rolling into the recess 16^a as its upper apex 26^a swings out to clear the top of the axle. With this embodiment less metal has to be removed from the axle than in the first embodiment.

30 In the embodiment of Figs. 8 and 9 a simpler form is shown, as the axle 15^b is merely flattened, the cutaway recess 16^b being therefore wholly exterior to the chord connecting the apices 17^b and 18^b. The jack aperture 25^b has upper and lower apices 26^b and 27^b which are necessarily spaced somewhat further apart than in the other embodiments. By a geometrical diagram it can readily be shown that if a cylinder is flattened at one side to a depth of 20% of its diameter, the resulting chord will be of the same length as the abridged diameter, namely 80% of the original diameter. With the axle reduced in this manner and the jack 40 aperture to the same extent, with preferably a slight margin of clearance, the jack can be readily slid from the axle when the flattened side of the latter is swung around to release position parallel to the direction of 50 extracting movement.

Having described a knitting machine embodying the present invention it is pointed out that the principles thereof may be variously embodied and that the claims are 55 not intended to be limited to details of structure or arrangement except to the extent set forth therein.

What is claimed is:

1. A straight hosiery knitting machine 60 having a series of independent jacks swingable in succession, a jack bed, and a jack supporting axle carried by the bed; each of the jacks being formed with an aperture to engage and fit the axle, such aperture being circular for substantially more than a semi-

circumference but with an open gap of sufficient width for disengagement from the axle, and the axle being circular to fit the jack aperture for substantially more than a semicircumference but formed with a recess 70 sufficient to permit the jack to be disengaged therefrom, the jack aperture gap and the axle recess being normally located at the same side of the axis so that the intact bearing surfaces of the jack aperture and axle are 75 in substantially uninterrupted bearing contact, and the axle being shiftable from its normal position wherein all of the jacks are confined but swingable thereon to its release position wherein any jack may be independently 80 disengaged from or engaged with the axle.

2. A knitting machine as in claim 1 and 85 wherein the jack aperture gap is of sufficiently greater circumferential extent than the axle recess that the normal swinging movement will not cause the apices of the jack bearing surface to overhang the axle recess.

3. A straight hosiery knitting machine 90 having a series of independent jacks swingable in succession, a jack bed, and a jack supporting axle carried by the bed; each of the jacks being formed with an aperture to engage and fit the axle, such aperture being circular for substantially more than a semicircumference but with an open gap for disengagement from the axle, and the axle being circular to fit the jack recess for substantially more than a semicircumference but formed with a concave or reentrant recess to 95 permit the jack to be disengaged therefrom, and the axle being shiftable between normal position wherein all of the jacks are confined but swingable thereon and release position wherein any jack may be independently 100 disengaged from or engaged with the axle.

4. A knitting machine as in claim 3 and 110 wherein the jack aperture circumference is intact for substantially more than 254° and the axle recess deep enough to receive the jack aperture apices during the extracting movement.

5. In a hosiery knitting machine of the straight type having a series of independent jacks swingable in succession, the combination with the series of jacks, of a jack bed, and a jack supporting axle carried by the bed; each of the jacks being formed with an aperture to engage and fit the axle, such aperture being circular for substantially more than 254° of circumference but with 115 an open gap of less than 106° but sufficient for disengagement from the axle, and the axle being circular to fit the jack recess for substantially more than a semicircumference but formed of crescent shaped section with a reentrant recess sufficient to admit the 120 apex of the jack aperture and permit the 125

jack to be disengaged therefrom, and the axle being shiftable between normal position wherein all of the jacks are confined but swingable thereon and release position 5 wherein any jack may be independently disengaged from or engaged with the axle.

In testimony whereof, this specification has been duly signed by:

ERNEST A. FEUSTEL.
